United States Patent Office

Des. 186,205

Patented Sept. 22, 1959

186,205

PLASTIC FIGURED TEXTILE FABRIC

Richard C. McEwan, Lloyd's Harbor, N.Y., assignor to Riegel Textile Corporation, a corporation of Delaware

Application July 28, 1958, Serial No. 51,955

Term of patent 14 years

(Cl. D87—3)

Fig. 1

Fig. 2

Fig. 1 is a plan view of a plastic figured textile fabric incorporating my new design; and

Fig. 2 is an enlarged sectional detail taken substantially on the line 2—2 in Fig. 1.

I claim:

The ornamental design for a plastic figured textile fabric, as shown.
